UNITED STATES PATENT OFFICE.

SAMUEL L. MARSH, OF NEW YORK, N. Y.

OIL PURIFIER.

Application filed February 9, 1921. Serial No. 443,531.

To all whom it may concern:

Be it known that I, SAMUEL L. MARSH, a citizen of the United States, and residing at New York, N. Y., have invented certain new 5 and useful Improvements in Oil Purifiers, of which the following is a specification.

This invention relates to the purification or cleansing of oil in its natural state as it comes from the wells, sumps, tanks, streams 10 or pipe lines and its object is to remove from the oil, its impurities such as water, sand, gas and the like by means of a continuously operating process and apparatus.

This invention is a continuation of my 15 patent application No. 341,852, filed December 2nd, 1919 which prior application relates broadly to the removal of the sand and water or the like from the oil and to specific means for doing it whereas this invention 20 relates to the addition thereto of means for removing the gas from the oil and to new means and arrangements of means for removing from the purifier, the sand, water, and oil.

25 I have shown one embodiment of my invention which is the best of which I am at present informed but it is to be understood that this is shown in an illustrative sense and not a limiting one for the invention is capable of a number of different embodiments. The embodiment is illustrated 30 in the accompanying drawings in which—

Fig. 1 is a side elevation with parts in section;

35 Fig. 2 is a plan view; and

Fig. 3 is an end view.

In the drawings, the numeral 11 represents a casing of varying width and depth 40 having an inlet 12, curved side walls 13 and 14, an end wall 15, and an inclined bottom 16. The bottom 16 is provided with a false 45 bottom 17 or a central channel of varying depth, varying from nothing at the upper end to several inches in depth at the outlet 18 from the casing. 19 represents curved 50 ribs on the bottom 16 of the casing leading to the channel 17 and 20 represents curved ribs on the side walls 13 and 14 leading downwardly to the outlet 18. 21 represents 55 supporting legs for the casing.

The outlet 18 is provided with a vertical 60 chamber 22, which may be made a part of a siphon or other suction, having an outlet 23 whose axial plane is slightly lower than 65 that of the inlet 12. The outlet 23 is connected to a sewer below the casing or basin

whereby the suction or siphonic action is produced. At the upper part of the siphonic or suction chamber 22 is a cleaning plug 24 and at the lower part is a valved 60 exit for removing the sand. This valve is numbered 25 which permits the sand to pass into a sand drum or collector 26 from which the sand may be removed by means of valve 27, when valve 25 is closed. 30 represents 65 the top of the casing 11. 31 represents a downwardly inclined deflector placed near the inlet 12 and this deflector may be slightly curved. 32 and 33 are additional deflectors the first of which is preferably inclined 70 oppositely to the deflector 31 and the second is preferably vertical in position. I do not limit myself to any specific number or character of baffles.

On the top 30 of the tank, I provide a gas 75 collecting dome 35 in the top of which is located a regulatable check valve 36 connected to a pipe 37 conveying the collected gas to any suitable container. 38 represents a pipe upstanding in the casing 11, into which the 80 collected or purified oil is adapted to flow and 38 and 39 represent any suitable means for adjusting the height of the pipe. The pipe 38 is connected by piping 40 to a bull-head 41 for collecting any gas which may 85 have escaped from the casing 11 due to any excess pressure therein. 42 is a connection for conveying any gas from the bull-head 41 to the pipe 37 and 43 is an oil outlet from the bull-head. 90

In operation, the oil in an impure state as it comes from a well, sump or pipe line, flows through the inlet 12 under pressure or gravity into the purifier, which is maintained full of liquid up to the dotted line 95 indicating the level thereof. Impact against the deflector 31 causes an oblique change of direction of flow of the mixture without emulsification thereof and thereby disturbs the equilibrium of the components of the oil 100 mixture so that the oil particles force their way upwardly whereas the sand and water pass down the incline.

This is duplicated but to a lesser degree by each of the succeeding deflectors. 105

Due to the peculiar construction of the false bottom or channel 17 together with the curved sides 13 and 14, the water flows downwardly at an accelerated speed so that by the time the water has passed the outlet 110 18 and reached the bottom of chamber 22, it has gathered momentum enough to carry

it up and out of the outlet 23 to waste. That is, the depressed channel 17 causes a flow of water to the outlet 18 which is accelerated as it descends and this acceleration of the water aided by the impurities directed downwardly by the ribs, tend to cause all the liquid impurities to bounce upwardly as it were, after they pass through the outlet 18 and get into the chamber 22. In other words, all the sediment or impurities after reaching the bottom of the chamber 22 due to this bouncing, are kept in violent agitation which permits suction on the outlet 23 to act upon the impurities to carry the lighter ones over the outlet. The sand or other solid impurities mixed with the water being so much heavier, pass out of the bottom of the chamber 22 through the medium of the valve 25 and are collected in the tank 26.

The shape of the side walls, plus the shape of the depressed channel plus the slanting bottom create, under the quiescent body of oil, a circular washing turbulence or eddies which terminate, or are pulled to, the outlet 18 where the velocity of the currents becomes the greatest. This has the effect of agitating, washing and sucking all the suspended matter (below the quiescent body of oil) out of the liquid, down and through the outlet 18.

The depressed channel as it increases in depth, causes an increasing flow of water in it towards the outlet 18 and this increase of both volume and speed of the water in the channel in turn causes a suction toward the outlet 18 where it is the strongest. This setting up of the washing currents has the result of causing the purification of the oil to be highly effective.

As the purified oil accumulates in a quiescent body in the upper part of the casing, it overflows by either force or gravity through the outlet pipe 38 and the piping 40 to a bull-head and thence to a reservoir where it is stored until used. As more or less oil is purified and rises to the top where it remains quiescent irrespective of the downward flowing therebeneath, the pipe 38

is raised or lowered so that only the purified oil will flow therethrough.

The oil during purification and afterwards due to its disturbance and turbulence, gives off a certain amount of gas which rises into the collecting dome 35 from whence it is conveyed to a suitable storage place by means of the pipe 37.

It is to be understood if this device should be used in connection with impure oil in which it is not desired to collect the gaseous impurities, the present device can be used without the gas collector 35. Obviously the ribs 19 and 20 could be replaced by small channels so long as the resulting structure has the same guiding function as the ribs.

What I claim is:

1. A method of continuously purifying petroleum oil which consists of disturbing the ingredients of the impure oil, causing the oil to move upwardly into a relatively quiescent body of purified oil, causing the liquid impurities in the oil to flow downwardly below the quiescent body at a uniformly accelerated speed, separating the liquid and the solid impurities, and collecting the gaseous impurities from the oil above the quiescent body.

2. In combination in an oil purifier having oil flowing continuously therethrough, retarding means for disturbing the equilibrium of the oil mixture, channeled and ribbed means for separating the liquid and solid impurities from the oil and means for collecting the gaseous impurities arising from the oil.

3. In combination in an oil purifier having oil flowing continuously therethrough, retarding means for disturbing the equilibrium of the oil mixture, channeled and ribbed means for separating the liquid and solid impurities from the oil and adjustable means for automatically removing the purified oil from the purifier.

In testimony whereof I hereunto affix my signature.

SAMUEL L. MARSH.
